CONSTANTINE DEMETRIUS MACROPOULOS, OF NEW YORK, N. Y.

ROTARY RECTIFIER OF ALTERNATING CURRENT.

1,260,785.

Specification of Letters Patent. Patented Mar. 26, 1918.

Application filed January 31, 1914. Serial No. 313,526.

To all whom it may concern:

Be it known that I, CONSTANTINE DEMETRIUS MACROPOULOS, a subject of the King of Greece, and resident of New York city, N. Y., have invented a new and useful Rotary Rectifier of Alternating Current, of which the following is a specification.

This invention relates to rotary rectifiers for alternating current and has for its general objects to simplify the construction of rectifiers of this character, cheapen their cost of manufacture and improve their construction in such manner that the brushes thereof may be readily adjusted to synchronize the rotary commutator bars with the alternating current and further insure the invariable engagement and disengagement of the brushes with the commutator bars at the intended time. A further object of the invention is to eliminate sparking at the instants of engagement and disengagement of the brushes with the commutator bars and remove the danger of short circuiting now usually present in known rectifiers. In realizing this object of the invention, in the preferred form of the improvements, the current usually lost in sparking is led in a different circuit to a storage battery and recovered for useful work. Other objects of the invention will appear at greater length hereinafter in connection with the description of the accompanying drawings, in which—

Figure 1 is a view in end elevation of the improved rectifier.

Fig. 2 is a view partly in longitudinal section and partly in side elevation of the rectifier shown in Fig. 1, the section being taken along the plane indicated by the broken line 2—2 of Fig. 1 and looking in the direction of the arrows.

Fig. 3 is a sectional view taken along the horizontal plane indicated by the line 3—3 of Fig. 1 and looking in the direction of the arrows.

Figs. 4 and 5 are conventional showings, somewhat diagrammatic in nature, of the commutator, projected, and the relation of the brushes to the conducting teeth of the commutator.

Fig. 6 is a diagrammatic view illustrating the disks, conductor bars, collector rings and circuits.

The rotary rectifier comprises generally a base *a* on which are supported bearing pieces *a'* in which is journaled the rotating

shaft *b* of the rectifier. On this shaft is supported the commutator which may be made as a laminated construction, comprising generally a series of metallic commutator disks *c*, *d*, *e*, insulated from one another by interposed disks *f* of suitable insulating material. These commutator disks are also insulated from the supporting shaft *b* by means of a sleeve *g* of suitable insulating material. At the end of the shaft are supported two sets of collector rings *h*, *h* and *i*, *i* with which engage suitable terminal brushes *h'*, *i'* by which the direct current is led off in a manner which will be understood. These collector rings are, of course, insulated from the shaft *b* and from one another as by interposed insulating disks *H*.

Before describing in detail the electrical connections and the relation of the current phases to the rectifier elements the purely structural improvements will be described in some detail. The commutator disks *c*, *e*, are connected for one half the commutator to a conductor rod *k* which is connected electrically to the positive ring *h* while the corresponding rings of the other half of the commutator are connected to a separate conductor rod *l* which is, in turn, in contact with the ring *h* at the negative side of the system. The interposed disks *d* between the disks *c* and *e*, are perforated, as at *d'*, to permit the conductor rods *k*, *l*, to pass therethrough without contact. At another portion of the commutator the alternate disks *c*, *e*, are perforated, as at *c'*, *e'*, to receive without contact other conductor rods *m*, *n*, which are in electrical engagement with the interposed metallic disks *d* and extend, respectively, to the positive and negative rings *i*, of a secondary electrical circuit for a purpose which will appear.

One important feature of the invention has to do with the construction of the commutator disks *c*, *d*, *e* to which the current passes from the brushes *o* of the alternating current circuit. These metallic disks *c*, *d*, *e*, are each formed with, or else carry, segmental contacts or raised portions *c'*, *d'*, *e'* which may properly be likened to teeth, and with which the respective brushes *o* come into engagement at proper times during rotation of the commutator.

The brushes *o* are supported on a swinging frame *p* on which are provided segmental gears *p'* engaged by worms *p''* rotatable through suitable hand wheels *p'''* on the end

of the worm shaft. Each of the brushes *o* is pressed upward yieldingly toward the teeth of the commutator by means of a suitable leaf spring *q*, this tension insuring snug electrical engagement between the brush and each tooth as it is brought into engagement with the brush.

The improved structural features of the rectifier have now been pointed out. For 10 an understanding of the operation of the rectifier, reference is first to be had to Fig. 4 for a description of the application of the rectifier to a three-phase six-wire alternating current circuit. In this figure, the brushes 15 *o* are shown diagrammatically in their relation to the periphery of the commutator proper and there is indicated the relation of these brushes at various times to the teeth of the respective commutator disks by 20 which the current from the brushes is fed to the commutator for transmission, rectified, to the direct current circuit. The teeth *c*², *e*², on the disks *c*, *e*, are so disposed with relation to one another and to the alternations of the circuit as to make contact with 25 the respective brushes at such times and for such duration as to insure the passage of current in its proper phase to the proper ring *h* for transmission to the direct current circuit. These teeth *c*², *e*² are likewise 30 so disposed to one another as to insure contact with the respective brushes at such times and for such duration as to complete the direct current circuit at the negative side 35 thereof. In the three-phase six-wire circuit illustrated the three wires marked 1 lead to such brushes as will engage successively with the proper teeth *c*², to lead the current through the conductor rod *k* to the collector 40 ring *h* at the positive side of the direct current circuit. The three wires marked 1^a are 45 connected to such brushes *o* as will make contact successively with the teeth *c*² at the other end of the commutator and will complete the circuit through the conductor rod 50 *l* connected with the collector ring *i* at the negative side of the direct current circuit. The three wires marked 2 are connected with such brushes as will engage successively 55 with the teeth *e*² of the disks *e* and insure the transmission of current through the conductor bar *k* to the positive ring *h* of the direct current circuit in proper relation to the phases of the current of these wires and 60 also in proper relation to the phase of the current in the other three wires 1. In like manner the wires 2^a complete the negative side of the direct current circuit by engagement of their brushes *o* with the proper teeth *d*² of the disks *d* at the other end of the commutator which disks are connected, in turn, 65 through the conductor bar *l* with the negative ring *h*.

The construction thus far described while 70 entirely feasible and insuring that certainty

of operation and degree of adjustment which is necessary in securing synchronism and rectification in a device of this kind, might be open to the usual objection of sparking at the brushes and danger of short circuiting. Accordingly, the improved commutator makes provision for the elimination of 75 sparking and short circuiting. Such provision is found in the interposed commutator disks *d* which are connected at different ends of the commutator through the conductor bars *m*, *n*, to positive and negative collector rings *i* of a secondary electrical circuit in which may be included a storage battery shown clearly in Fig. 4. The 80 disks *d* carry or have formed thereon teeth *d*² which are disposed opposite and overlapping the ends of each of the teeth *c*², *e*², of the disks of the main circuit and the brushes *o* are so formed as to contact at the 85 same time with one of the teeth of one of these disks *c*², *e*², and with one of the teeth *d*² on the proximate disk *d*. In this manner it is assured that as one of the teeth *c*², *e*² runs off the brush *o*, the brush will contact 90 for an instant with this tooth and also with the tooth *d*² of the proximate disk so that the current which ordinarily would be lost in sparking at the time of engagement or disengagement of the brush with the conductor is deflected to the tooth *d*² and thence through the proper conductor bar *m*, *n*, to the rings *i* of the secondary circuit. Further, the danger of short circuiting is 95 prevented by inclusion of the conductor 100 teeth *d*² of the secondary circuit in proper relation to the teeth *c*², *e*² of the main commutator disks. The current derived through these teeth *d*² in the secondary circuit is 105 led to the storage battery and there stored 110 for use.

The improved rectifier may be rotated by any convenient motor and its speed of rotation will, of course, be fixed in accordance with the frequency of the alternating current and the number of teeth on the commutator disks. The brushes *o* on the adjustable frame will be moved through the hand wheels *p*³ so as to insure synchronism between the alternations in the circuit and the 115 conductor elements of the commutator.

It is quite evident that the principle involved in the invention may be employed to equal advantage in a rectifier in which other phase and wire systems are employed. 120

Many mechanical alterations in the construction may be made without departing from the spirit of the invention as, for instance, the connections through the brushes to both the alternating and direct current 125 circuits may be of any known character, the size of the disks and their teeth may be proportioned in conformity with the usual electrical requirements and the teeth of the disks may be either integral therewith or secured 130

thereto. Reference is to be had to the appended claims for an understanding of the scope of the invention.

I claim as my invention:

1. A rotary rectifier comprising a commutator shaft, positive and negative collector rings, a commutator comprising a series of insulated commutator disks provided with segmental contacts and connected to the positive collector ring, a second series of insulated commutator disks alternating with the disks of the first series also provided with segmental contacts offset with respect to the contacts of the first series and connected to the negative collector ring, and a third series of insulated commutator disks interposed between successive rings of the first and second series, provided with segmental contacts between and overlapping the ends of the contacts of adjacent disks and connected to a secondary circuit, brushes for contact with the segmental contacts of the disks of the first and third series and connected to one side of the working circuit, and other brushes for contact with the disks of the second and third series and connected to the other side of the working circuit.
2. A rotary rectifier comprising a commutator shaft, positive and negative collector rings, a commutator comprising an insulated commutator disk provided with segmental contacts and connected to the positive collector ring, a second insulated commutator disk provided with segmental contacts offset with respect to the contacts of the first disk and connected to the negative collector ring, and a third insulated commutator disk provided with segmental contacts overlapping the ends of the contacts of the other two disks and connected to a secondary circuit, a brush for contact with

the contacts of the first and third disks and connected to one side of the working circuit, and a brush for contact with the contacts of the second and third disks and connected with the other side of the working circuit. 45

3. A rotary rectifier comprising a commutator shaft, a commutator composed of a series of spaced disks, positive and negative collector rings, conductor bars connected to said disks and to the respective rings, independent disks interposed between said first named disks, independent positive and negative collector rings in electrical connection with said last named disks, segmental teeth on all of said disks and brushes to engage said teeth, the teeth on the interposed disks being arranged opposite the ends of the teeth on the proximate spaced disks. 50 55

4. A rotary rectifier comprising a commutator formed of a series of insulated disks, conductor rods extending through said disks and in electrical engagement with alternate disks, independent conductor rods 65 extending through said alternate disks and in electrical engagement with the remaining disks, positive and negative collector rings for the respective conductor rods, said collector rings being insulated from each 70 other and disposed in independent direct current circuits, segmental teeth on said disks, the teeth on the disks in one of said circuits being disposed at the ends of the teeth on the disks in the other of said circuits, and brushes to engage said teeth. 75

In testimony thereof, I have signed my name to this specification, in the presence of two subscribing witnesses.
